[57] CLAIM

The ornamental design for a pattern for a conveyor belt, as shown and described.

DESCRIPTION

FIG. 1 is a fragmentary perspective view of a pattern for a conveyor belt showing our new design;

FIG. 2 is a top plan view thereof;

FIG. 3 is a side elevational view thereof taken along the line 3—3 of FIG. 2; and

FIG. 4 is a fragmentary, enlarged sectional view thereof taken along the line 4—4 of FIG. 2.

The bottom side of the conveyor belt having the pattern on the top is flat and unornamented. The pattern of the conveyor belt repeats itself across the entire surface of the conveyor belt.
